UNITED STATES PATENT OFFICE

CHARLES A. STYER, OF WILKINSBURG, PENNSYLVANIA, ASSIGNOR TO WESTINGHOUSE ELECTRIC & MANUFACTURING COMPANY, A CORPORATION OF PENNSYLVANIA

METHOD OF AND MEANS FOR PROVIDING INERT ATMOSPHERES

Application filed December 29, 1923. Serial No. 683,379.

My invention relates to the removal of oxygen from mixtures of gases containing the same, more particularly to the provision of inert atmospheres in electrical apparatus.

5 In transformers, circuit breakers, oil switches, and the like, there is provided within the vessel containing the apparatus, an insulating oil, above which is a space to allow for expansion and contraction of the oil under normal operating conditions. It is desirable to remove oxygen from the space above the oil, and to prevent the access of oxygen thereto, because of the detrimental effects thereof. It has been found that oxygen reacts with the oil, producing a sludge which lowers the insulating properties of the oil. During the operation of the apparatus, arcing may occur with the production of combustible gases, which, if mixed with oxygen, 10 may give rise to explosive mixtures. These mixtures are sometimes ignited by arcs within the apparatus, damaging the same and endangering the safety of workmen.

To overcome these difficulties, it has been proposed to provide an atmosphere in the space above the oil, which is inert in that it does not combine with the oil and does not form explosive mixtures with combustible gases produced from the oil. 25 My invention is directed to such devices, it being among the objects thereof to provide an inert atmosphere by simple and effective means.

It is a further object of my invention to provide a method of and a means for producing inert atmospheres, which shall be positive in its action, incapable of deterioration on standing, and which shall not require any appreciable amount of maintenance.

40 In practising my invention, I provide a carbonaceous material and heat the same to a temperature sufficiently high to facilitate the reaction of the said material with oxygen. The mixture of gases containing oxygen are passed through the heated material and the oxygen is caused to combine with the carbon to form carbon dioxide, which is inert. More specifically, I prefer to use ashless material, such as sugar carbon, and I provide means for replenishing the carbon as it is consumed.

In the accompanying drawings, constituting a part hereof, and in which like reference characters indicate like parts,

Figure 1 is an elevational view of a transformer, a part of the casing being broken away to show my device in position;

Fig. 2 is a vertical cross-sectional view of one form of my device; and

Figs. 3, 4, 5 and 6 are diagrammatic, vertical sectional views of various modifications of my invention.

Within the casing or vessel 1 is a transformer body 2 covered with oil 3. Terminals 4 and 5 connected to the transformer body, pass through the cover 6 of the casing 1. A container 7, embodying my invention, projects into the space 8 above the oil level in the casing 1. The container 7 is provided with an annular flange 9, which rests upon the cover 6 of the transformer and is secured thereto by any suitable means, as by a welded joint 10. The major portion of the container is in the space 8.

The lower end of container 7 is provided with heat-insulating material 11, through which a passage 12 is formed. A gauze 13 is embedded in insulating material 11 across the passage 12. A pair of heating elements 14 and 15 are also secured in the insulating material at points above the gauze 13. The heating elements may be of any desired construction, but preferably they are formed by first providing a frame of sheet-insulating material such as mica, and threading therethrough and across the central opening thereof, a plurality of turns of resistance wire. Carbonaceous material 16, preferably sugar carbon, is placed on gauze 13 so that it covers both heating elements.

45 A passage 17 offers communication between the passage 12 and the opening 18 in container 7. An additional passage 19, communicating with the outside air at the opening 20, has its outlet between the heaters 14 and 15. A hopper 21, having a mass 22 of carbonaceous material, communicates with the body 16 of the same material and provides a continuous supply of the same. A cover 23 is secured to the top of container 7 in any suitable manner.

In Fig. 3, I have shown a slight modification of my invention, wherein I provide a container 24 having a gauze 25 secured therein and a heating element 26 with carbonaceous material 27 covering the same. Passages 28 and 29 allow free circulation of gases through the material. The circulation may be either forced or thermo-siphonic or both.

A similar structure is shown in Fig. 4, with the exception that, instead of a single passage 28 at the lower end of the container 24, I have provided an enlarged passage 30 and a concentric passage 31, which may communicate with the outside air. This provides separate paths 31 and 30 for the forced and the thermo-siphonic circulation, respectively.

In the embodiment shown in Fig. 5, there is provided a plurality of concentric gauzes 32 and 33, the top of gauze 32 being closed by member 34. The two gauzes are connected together at their lower ends by the annulus 35. The space therebetween is filled with carbonaceous material 36, which surrounds the heater 37. The upper portion 38 of the container constitutes a storage space for reserve material 39. A tube 40, communicating with the outside air, projects into the space 41 and provides an additional passage 42 similar in function to that shown in Fig. 4.

The embodiment illustrated in Fig. 6 is very similar to that shown in Fig. 5, with the exception that the thermo-siphonic circulation is caused to pass through passages 44 and 45, and the forced circulation through tube 46, which is connected to the outside air.

The operation of my invention, as applied to the embodiment shown in Fig. 2, is as follows: The apparatus is filled with carbonaceous material and the heaters 14 and 15 connected to any suitable source of energy, not shown. The source of energy may be the transformer itself, or it may be an independent circuit. Any suitable reaction temperature may be used. I have found that 600° C. provides a sufficiently rapid rate of oxidation for most purposes. If desired, a lower temperature, even as low as 300° C. may be used, and it is obvious that higher temperatures are suitable.

Owing to the higher temperature of the heaters 14 and 15, a thermo-siphonic circulation is induced in the space 8 above the oil 3, whereby the gases enter passage 12, pass through the heaters and the carbonaceous material into passage 17 and return to the space 8 through opening 18 in casing 7. In the passage through the heaters, any oxygen present is caused to combine with the heated carbon to form carbon dioxide, or, in some cases, carbon monoxide.

During the breathing of the transformer because of expansion and contraction of the oil, air is drawn in through tube 19, passing through heaters 14 and 15 where the oxygen is removed from the air by the heated carbon

and a mixture of nitrogen and carbon dioxide flows into space 8 by passages 12 and 17.

The various other modifications of my invention operate in a similar manner to that described in connection with Fig. 2.

It will be noted that I have provided various forms of apparatus wherein carbon is heated to a reaction temperature and gases passing therethrough are deoxygenated. The material is not affected by changes in atmospheric conditions and does not deteriorate on standing. The device removes not only the oxygen from the air being breathed by the transformer, but also removes any oxygen which may have been in the space 8 originally, or which may enter the said space accidentally because of leakage at points other than opening 20. Various changes may be made in the details of construction of my device within the scope of my invention, as will be apparent to those skilled in the art.

I claim as my invention:

1. Means for providing non-combustible inert atmospheres substantially of nitrogen and carbon dioxide comprising a container, a foraminous partition therein, carbonaceous material supported at least partly thereby, means for heating said material, means for passing gases from an independent source therethrough and means for by-passing other gases therethrough.

2. Means for providing non-combustible inert atmospheres substantially of nitrogen and carbon dioxide comprising a container, a foraminous partition therein, carbonaceous material supported at least partly thereby, means for heating a portion of said material and means for repeatedly passing gases through said heated portion of the material.

3. Means for providing non-combustible inert atmospheres substantially of nitrogen and carbon dioxide comprising a container, a foraminous partition therein, carbonaceous material supported at least partly thereby, means for heating a portion of said material, means for passing gases from an independent source through said heated portion of the material, means for by-passing gases through said material and a chamber associated therewith for holding an additional supply of material.

4. Means for providing non-combustible inert atmospheres substantially of nitrogen and carbon dioxide comprising a container, a foraminous partition therein, carbonaceous material supported at least partly thereby, means for heating said material and means for passing gases therethrough, including passages communicating with a closed vessel.

5. Means for providing non-combustible inert atmospheres substantially of nitrogen and carbon dioxide comprising a container, a foraminous partition therein, carbonaceous material supported at least partly thereby, means for heating said material, means for

passing gases therethrough, and means for supplying gases thereto, including passages communicating with a closed vessel, one of said passages being from the outside air to the said vessel.

5 6. Means for providing non-combustible inert atmospheres substantially of nitrogen and carbon dioxide comprising a container, a foraminous partition therein, carbonaceous material supported at least partly thereby, means for heating said material and means for passing gases therethrough, including passes communicating with a closed vessel, one of said passages being from the outside 10 air to the said vessel and another being wholly 15 within the same.

7. Means for providing non-combustible inert atmospheres substantially of nitrogen and carbon dioxide comprising a container, a 20 foraminous partition therein, carbonaceous material supported at least partly thereby, means for heating said material and means for passing gases therethrough, including 25 passages communicating with a closed vessel to allow both forced and thermo-siphonic circulation of gases.

8. Means for providing non-combustible inert atmospheres substantially of nitrogen and carbon dioxide comprising a container, a 30 foraminous partition therein, carbonaceous material supported at least partly thereby, means for heating said material and means for passing gases therethrough, including 35 passages communicating with a closed vessel to allow circulation through said material in a plurality of directions.

9. A method of providing non-combustible inert atmospheres substantially of nitrogen and carbon dioxide which comprises maintaining carbonaceous material at a temperature sufficiently high to facilitate the reaction thereof with oxygen and insufficient to combine with or crack hydrocarbon vapors and then passing oxygen-containing gases there- 45 through.

10. A method of providing non-combustible inert atmosphere substantially of nitrogen and carbon dioxide which comprises heating ashless carbon to a temperature sufficiently 50 high to facilitate the reaction thereof with oxygen and passing oxygen-containing gases therethrough.

11. A method of providing non-combustible inert atmospheres substantially of nitrogen and carbon dioxide which comprises maintaining carbonaceous material at a temperature sufficiently high to facilitate the reaction thereof with oxygen, passing and 55 by-passing oxygen-containing gases there- 60 through and replenishing the supply of material.

12. The combination with a tank having a gas space and a liquid therein, said liquid being capable of producing an explosive mix- 65 ture with gases contained in said space, of

means for rendering the gases in said space non-explosive comprising a container having means associated therewith for effecting a communication with said gas space, a foraminous support in said container and means in 70 said container for heating a combustible material for effecting a combination thereof with oxygen, whereby gases coming in contact with said material partially combine therewith and form non-combustible gas. 75

13. The combination with a tank having a gas space and a liquid therein, said liquid being capable of producing an explosive mixture with gases contained in said space, of means for supplying non-explosive gas to 80 said space comprising a container having means associated therewith for effecting a communication with a supply of gas and with said gas space, a foraminous support in said container and means in said container for 85 heating a combustible material whereby the gases coming in contact with said material partially combine therewith to form non-combustible gas.

14. The combination with a tank having a gas space and a liquid therein, said liquid being capable of producing an explosive mixture with gases contained in said space, of means for rendering the gases in said space non-explosive comprising a container, hav- 90 ing means associated therewith for effecting a communication with said gas space, a support for holding a combustible material, means in said support for heating said com- 95 bustible material whereby a portion of the gas supplied to said space is caused to react with said combustible material and render the resultant gas non-explosive. 100

15. The combination with a tank having a gas space and a liquid therein, said liquid being capable of producing an explosive mixture with gases contained in said space, of means for displacing said explosive gas with a non-explosive gas comprising a container having a communication with outside air and a communication with said gas space, a sup- 105 port in said container for holding a combustible material, said support being adapted to permit circulation of gas therethrough and means associated with said tank for permitting displacement of gas contained in said space by non-explosive gas. 110

16. The method of maintaining an inert atmosphere in a casing containing a liquid combustible with air and an electrical apparatus immersed in the liquid, which method consists in burning fuel and conducting the gaseous products of combustion into the casing to occupy the space above the liquid therein. 115

17. The method of maintaining an inert atmosphere in a casing containing a liquid combustible with air and an electrical apparatus immersed in the fluid, which method consists in burning fuel and circulating the 120 125 130

gaseous products of combustion through the casing above the liquid therein.

18. The method of preventing explosions in a casing containing a liquid combustible in air and an electrical apparatus immersed in the liquid, which method consists in burning fuel and conducting the gaseous products of combustion into the casing to occupy the space above the liquid and to exclude air from said space.

19. In testimony whereof, I have hereunto subscribed my name this 17th day of December 1923.

CHARLES A. STYER.
